US00D725068S

(12) **United States Design Patent**
Cho et al.

(10) **Patent No.:** **US D725,068 S**
(45) **Date of Patent:** **** Mar. 24, 2015**

(54) **WATCH PHONE**

- (71) Applicant: **Samsung Electronics Co., Ltd.**, Suwon-si (KR)
- (72) Inventors: **Chul-Yong Cho**, Seoul (KR); **Sang-Min Hyun**, Seoul (KR); **Sang-Chul Lee**, Namyangju-Si (KR)
- (73) Assignee: **Samsung Electronics Co., Ltd.**, Suwon-si (KR)

(**) Term: **14 Years**

(21) Appl. No.: **29/473,786**

(22) Filed: **Nov. 26, 2013**

(30) **Foreign Application Priority Data**

- May 29, 2013 (KR) 30-2013-0027961

(57) **CLAIM**

The ornamental design for a watch phone, as shown and described.

DESCRIPTION

FIG. 1 is a front perspective view of a watch phone showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines are for environmental purposes only and form no part of the claimed design.

1 Claim, 7 Drawing Sheets
